SKI BENCH

James G. Huebner, Fresno, Calif.

Application March 14, 1941, Serial No. 383,276

8 Claims. (Cl. 144—288)

My invention relates to a ski bench for finishing, edging, binding installation, waxing, and repairing skis.

Skis are formed with a camber extending the greater part of their length, and a curved forward end known as a shovel. In the process of manufacture, there are numerous operations to be performed upon them after they have reached this stage, some of the work being done in the factory, and some of the work being done in ski shops which sell or rent skis.

In many of the operations it is desirable that the ski be firmly supported along its entire length and securely retained in place. Various makeshift devices have been employed in an attempt to accomplish this, but so far as I am aware no one prior to my invention has devised a special work bench for this purpose.

It is an object of my invention to provide a special work bench for finishing, edging, binding installation, waxing, and repairing skis, in which the skis are firmly supported along substantially their entire length in either upright or inverted position. Thus the skis may be clamped upright on my ski bench for attaching bindings, sanding for refinishing, varnishing, etc. The skis may be clamped in an inverted position and equally well supported for routing, edging, scraping, waxing, and repairing.

A further object of my invention is to provide in a special work bench of the character described a recess to accommodate the rib on the upper surface of the skis.

A further object of my invention is to provide in a special work bench of the character described a removable insert which when in place, provides a curved upper surface conforming to the camber of the skis, and when removed provides a concave support conforming to the skis when inverted, and further including a recess for accommodation of the ski binding.

Other objects and advantages will become apparent as the description progresses.

In the drawing

Figure 1 is a side elevation of a ski bench embodying my invention, showing the insert in place and a ski clamped in position.

Figure 2 is a view similar to Figure 1 but partly in section, and with the insert removed and illustrating a ski clamped in an inverted position.

Figure 3 is a fragmentary sectional view on the line 3—3 of Figure 1.

Figure 4 is a sectional view taken on the line 4—4 of Figure 2.

Figure 5 is a fragmentary side view of the forward end of the bench illustrating a modified form of front clamp.

Figure 6 is a bottom plan view of the block 5 of the clamp shown in Figure 5.

Figure 7 is a fragmentary section taken on a line 7—7 of Figure 1.

Figure 8 is a view similar to Figure 7 illustrating a modified form of insert member.

On a pair of end pedestals 5 and supporting members 6 are secured longitudinal members 7 making up the table portion of the bench. These members 7 are disposed in pairs upon each pair of which may be positioned one ski designated S. For convenience I prefer to form the bench with two pairs of members 7 to accommodate a pair of skis. The members 7 are all identical. Each comprises two parts, a fixed lower section or member 8 and a removable insert member 9. Each member 8 has a curved tapered rear face 10, a curved tapered forward face 11 and an intermediate depression 12.

The member 9 fits the upper surface of the member 8, and seats thereon without auxiliary attachment.

The upper faces of the members 9 are curved to conform to the camber of skis when in normal position. The ski is clamped to the bench in this position as subsequently described, and is thereby supported along substantially its entire length.

For working on the skis in an inverted position, the members 9 are removed. I have provided hooks 13 to conveniently hold the members 9 when they are not in use. The tapered faces 10 and 11 of the members 8 are designed to conform to the contour of the skis when inverted, and the depression 12 accommodates the binding of the skis. Inasmuch as the binding extends substantially across the entire width of the skis, it is impossible to provide complete support in the region of the bindings, but as I have provided support for the skis when inverted along a substantial portion of their length, I have achieved by the design of my bench the maximum support obtainable, which has been found in practice to be adequate. When the skis are inverted the ribs R thereof extend downwardly into the space between the members 8.

The skis are held in position by clamps 14 at the rear end of the bench and 15 at the forward end of the bench. Skis are of different lengths, although the general camber thereof is the same, and to accommodate different length skis I have made the clamp 14 of a special design. It com-

prises a longitudinal rod 16 anchored between and parallel to the members 8 by cross bolts or pins 17. A clamping bolt 18 is formed with an eye 19 which is slideable on the longitudinal rod 16. The bolt 18 passes through a block 20 which has an overlying lip or extension 21, the latter of which is adapted to be forced down upon the rear end of the ski whether the ski is in upright or in inverted position. The block may be made of wood, metal, hard rubber, or any other suitable material. The part which contacts the ski may be faced with a cushioning material if desired.

It will be obvious that other forms of rear clamps may be employed.

The front clamp 15 is preferably used only when clamping the skis in upright position. This clamp is L shaped as illustrated in Figure 3, a threaded extension of which passes through the supporting member 6. That part of the clamp 15 which engages the ski may be covered with a cushioning material if desired.

For securing the skis at the forward end when inverted I prefer to use another form of clamp indicated as 22 in Figure 2. This clamp has a threaded section 23 which extends through the supporting member 6, an oblique section 24, and an upper flat extension 25 which engages the shovel of the ski and secures it tightly upon the curved forward end of the member 8 indicated by the reference numeral 26, which curved portion conforms to the curve of the shovel. That part of the clamp 22 which engages the ski may also be covered with a cushioning material.

A modified front clamp is illustrated in Figures 5 and 6. It comprises a cross pin 30 threaded at both ends and a pair of eye bolts 31 mounted on the pin outside the members 8, and secured by wing nuts 32. The eye bolts extend through a block 33, which can be tightened down by wing nuts 34. The block is preferably formed with a wedge shaped slot 35 which is shallow at the wide part of the slot and deep at the narrow end of the slot, to snugly engage the tip of the ski. In use, the wing nuts 32 may be used to set the position of the bolts 31, which is determined by the fit of the slot 35 on the ski, and the wing nuts 34 then screwed down to clamp the block 33 on the ski.

In operation, assuming that the insert members 9 are in position, the ski S or a pair of skis S is placed upon the bench in the position illustrated in Figure 1. The clamp 14 is shifted into the correct position, and the thumb nuts of the clamps 14 and 15 are screwed down. Work may then proceed upon the upper surface of the ski, such for example as finishing, installing bindings, and repairing.

When work on the top of the ski is finished, the clamps may be loosened, the ski removed, and the insert members 9 taken out and placed in the hooks 13.

After the insert members 9 have been removed, the skis may then be inverted and placed on the bench as illustrated in Figure 2, whereupon the clamp 14 is screwed down on the tail or heel of the ski, and preferably a clamp such as illustrated at 22 replaces the clamp 15 and is screwed down on the shovel of the ski. The bindings indicated at B are accommodated in the recess 12. While the skis are thus clamped, operations such for example as routing, edging, scraping, waxing, and repairing may be performed.

The illustration of the pedestals 5 is by way of example only. These pedestals may be supported upon a floor, or they may be eliminated entirely

and replaced by some other form of frame or supporting means. The supporting member 6 may itself be the top of a table or bench. I prefer to mount the pairs of members 7 in reasonably close proximity, with a solid member between as illustrated, providing for easy accessibility of both skis of the pair, as well as a receptacle for tools. An adjunct, which is not a part of this invention, may be an electric socket mounted in the member 6 between the pairs of members 7. Such a feature facilitates the use of electric tools in connection with the bench.

While two pairs of inserts 9 have been shown and described, it would be equivalent to utilize a single wide member in place of each pair as illustrated in Figure 8.

Having described my invention, what I claim as new and desire to secure by Letters Patent is:

1. A work bench for supporting skis when performing operations thereon comprising: a base, an inverted ski supporting surface permanently mounted on the base having a concave face substantially conforming to the camber of an inverted ski and including a central longitudinal space to accommodate the rib of a ski and an intermediate depression to accommodate the binding of a ski, removable insert members having a surface substantially conforming to and adapted to seat securely on the concavity of said inverted ski supporting surface in place of a ski and having a convex upper face conforming to the camber of an upright ski and providing a supporting surface for an upright ski, and means to clamp a ski securely on either of said supporting surfaces.

2. A device as described in claim 1 in which the concave face of the inverted ski supporting surface merges into an abrupt convex forward end conforming to the shovel of an inverted ski.

3. A work bench for supporting skis when performing operations thereon comprising: a base, an inverted ski supporting surface permanently mounted on the base having a concave face substantially conforming to the camber of an inverted ski and including a central longitudinal space to accommodate the rib of a ski and an intermediate depression to accommodate the binding of a ski, removable insert members having a surface substantially conforming to and adapted to seat securely on the concavity of said inverted ski supporting surface in place of a ski and having a convex upper face conforming to the camber of an upright ski and providing a supporting surface for an upright ski, and means to clamp a ski securely on either of said supporting surfaces, said means including a tail clamp adapted to engage the heel of the ski and including means to shift the clamp longitudinally of the supporting surface to clamp skis of different lengths.

4. A work bench for supporting skis when performing operations thereon comprising: a ski supporting surface including parallel spaced apart members, a tail clamp for securing the tail of a ski to the supporting surface including a rod mounted between the said members longitudinally thereof, a bolt slidably mounted on said rod, and a clamping element on the bolt adapted to overlie the heel of the ski.

5. A work bench for supporting skis when performing operations thereon comprising: a base, an inverted ski supporting surface permanently mounted on the base having a concave face substantially conforming to the camber of an inverted ski and including a central longitudinal

space to accommodate the rib of a ski, a removable insert having a surface substantially conforming to and adapted to seat securely on the concavity of said inverted ski supporting surface in place of a ski and having a convex upper face conforming to the camber of an upright ski and providing a supporting surface for an upright ski, and means to clamp a ski securely on either of said supporting surfaces.

6. A device as described in claim 5 in which the concave face of the inverted ski supporting surface merges into an abrupt convex forward end conforming to the shovel of an inverted ski.

7. A work bench for supporting skis when performing operations thereon comprising: a base, an inverted ski supporting surface permanently mounted on the base having a concave face substantially conforming to the camber of an in-

verted ski and including a central longitudinal space to accommodate the rib of a ski and an intermediate depression to accommodate the binding of a ski, a removable insert having a surface substantially conforming to and adapted to seat securely on the concavity of said inverted ski supporting surface in place of a ski and having a convex upper face conforming to the camber of an upright ski and providing a supporting surface for an upright ski, and means to clamp a ski securely on either of said supporting surfaces.

8. A device as described in claim 7 in which the concave face of the inverted ski supporting surface merges into an abrupt convex forward end conforming to the shovel of an inverted ski.
